[57] ABSTRACT

An alkali metal hydroxide and water solution having incorporated therein nitrogen-containing anionic surfactants combined with a polyhydric alcohol to form the active concentrate of a composition for cleansing food residue and soil from preheated surfaces of cooking ovens, grilles and the like. The particular anionic surfactants present in the concentrate have the important function of inhibiting the corrosive action of the concentrate on the human skin and mucous tissues and consist specifically of the sodium salts of the condensation product of coconut fatty acids with a complex of polypeptides and amino acids derived from proteins (Maypon SK), of a complex of polypeptides and amino acids derived as a hydrolysate from proteins (Polypeptide No. 37) and of an amido methylated lauric acid (Sodium N-Lauroyl Sarcosinate Sarksyl NL-97). The concentrate may include a thickening agent to render it surface adhering and additionally may be packaged in an aerosol container for expulsion therefrom by a propellant with or without a foam-forming and foam-stabilizing agent.

1 Claim, No Drawings

ALKALINE OVEN CLEANING COMPOSITION

This application is a continuation application of application Ser. No. 776,261, filed Nov. 15, 1968, now abandoned, which in turn was a continuation-in-part of application Ser. No. 517,114, filed Dec. 28, 1965, now abandoned.

The present invention relates to a new and improved composition for and method of quickly and expeditiously removing and cleaning from a surface, such as the interior surface of a cooking oven, all adherent residue of burnt-on fat or other deposits of greasy or oily character.

Among the principal objects of the present invention is the provision of a cleanser composition which may be contained in and dispensed from a pressure-tight container having a conventional aerosol dispensing valve, said concentrate being characterized by the fact that it is in the form of a concentrate which includes, inter alia, an aqueous solution of caustic alkali which is non-corrosive and so produces no harmful effects on the skin should any of the concentrate contact the skin during use of the cleansing composition. The concentrate is dispensed from the aerosol package by a propellant contained therein, which propellant is completely inert with respect to and substantially insoluble in the concentrate. Instead the propellant forms with the concentrate, upon shaking of the package, an emulsion from which the propellant is gradually released to thereby effect upon actuation of the aerosol dispensing valve, discharge of the concentrate from the aerosol package to the surface to be cleaned. Since the propellant basically remains not dissolved in the concentrate, where it is of a specific gravity higher than that of the concentrate, it is normally disposed as a liquid in the bottom of the aerosol container in underlying relation to the concentrate. However, when the aerosol package is vigorously shaken to form the above-mentioned concentrate-propellant emulsion and the aerosol discharge valve is then opened, a proportion of the propellant in the form of a vapor is released from the emulsion into the head space of the container and maintains therein a gaseous pressure sufficient to expel the emulsion from the container, so that the concentrate, upon its discharge from the container and impingement upon the surface being cleaned, is converted into a foam by the expanding action of the gas entrained therein.

In accordance with the principles of the present invention, the cleanser concentrate contains as its essential constituents (1) caustic alkali (which may be either sodium hydroxide or potassium hydroxide); (2) a nitrogen-containing surfactant of the anionic class, with or without a fatty acid soap as a foam stabilizing agent; (3) a high boiling, essentially non-evaporative polyhydric alcohol; and (4) water in which the foregoing constituents are dissolved to form an aqueous solution thereof. As has been indicated above, the propellant employed in conjunction with such aqueous solution of concentrate packaged in an aerosol container is of a kind which not only is neither substantially hydrolyzable or degradable in the presence of the concentrate but also is substantially insoluble therein so that it combines with the concentrate only in the form of an emulsion.

The caustic alkali employed, either sodium hydroxide or potassium hydroxide, is readily soluble in water, the proportion of alkali used based on the total weight of the concentrate ranging from 0.5 to 5 percent as

against a water content of from 30 to 70 percent by weight of the concentrate. This exceedingly small ratio of caustic alkali to water in the concentrate provides important advantages for the concentrate of the present invention, among which advantages may be listed the fact that water is the least expensive solvent and so materially reduces the cost of the concentrate, and the fact that the relatively high proportion of water present in the concentrate makes it unnecessary to water down the soiled surface being cleaned as a preliminary to application of the cleanser composition and effective activation thereof.

Another most important object of the present invention is to provide a concentrate in the form of an aqueous solution of caustic alkali combined with alcohols and anionic surfactants which not only very markedly inhibits corrosive action of the caustic on the skin but also is not corrosive to ferrous metals of which aerosol containers are made.

Ordinarily aqueous solutions of caustic alkali, particularly when the ratio of caustic alkali to water is high, are quite corrosive to human skin and upon contact cause burns which are of an irreversible reaction or nature. The addition of surface active agents as generally employed in combination with caustic alkali for increasing its saponifying action upon food residue or other fat material in adherent contact with the surface to be cleaned increases the harmful action of the caustic on the skin.

I have found that the use of certain nitrogen-containing anionic surfactants combined with polyhydric alcohols in an aqueous solution containing not more than 5 percent of caustic alkali and from 30 to 70 percent of water by weight of the concentrate provides a concentrate which is effective for use in quickly and easily cleaning adherent food residue and soil from the surfaces of cooking ovens, barbecue grilles and other surfaces made of alkali resistant materials, which has no corrosive action on the skin nor on ferrous metals, which is relatively non-volatile under normal conditions of use and may be safely admixed with various chlorofluoro-carbon base and hydrocarbon propellants and mixtures thereof for use in aerosol containers to yield a non-flammable pressure-expelled cleansing composition, which is compatible with a fatty acid soap when introduced into the concentrate for the production of a stabilized foam, and which may be safely applied to a soiled surface that has been preheated to a temperature of about 200° F. to effectively increase the rate of saponifying reaction of the concentrate upon the carbonized and non-carbonized fats and soil residue desired to be removed from the surface to be cleaned. Further, I have found that in use of the concentrate of the present invention it is not necessary to employ vinegar or any other agent to neutralize the caustic alkali, nor is it necessary that the user of the concentrate wear gloves or other protective articles, since the caustic in the concentrate is so inhibited as to have no corrosive effect upon the human skin and mucous membranes. By "concentrate" as used herein is meant the aqueous solution of caustic alkali, polyhydric alcohols and anionic surfactants hereinafter specifically described with or without additives and excluding therefrom the propellant.

The anionic surfactants employed in the concentrate of the present invention may be any one or a mixture of the following:

1. "Maypon SK" (manufactured by the Maywood Division of Stepan Chemical Company), consisting of the sodium salt of the coconut fatty acid amide of protein hydrolysate (complex polypeptides obtained from protein hydrolysis), having the structure:

wherein

n is an integer averaging 4 which is controlled by the degree of hydrolysis,

R represents hydrogen or hydrocarbon groups having from 1 to 7 carbon atoms,

R_1 represents coconut fatty acid, and

M represents sodium, potassium, ammonium, triethanolamine and other organic amines.

This compound, MAYPON SK, contains from 36 to 43 percent of the characterizing sodium salt as its active ingredient and from 14.4 to 16.9 percent proteins, as computed from Kjelda h , Nitrogen determinations showing 2.3 to 2.7 percent Nitrogen.

2. "Polypeptide No. 37" (manufactured by Maywood Division of the Stepan Chemical Company), consisting of the sodium salt of a complex of polypeptides and amino acids derived as a hydrolysate from protein degradation, having the structure:

wherein

n is an integer averaging 20 which is controlled by the degree of hydrolysis,

R represents hydrogen or hydrocarbon groups having from 1 to 7 carbon atoms, and

M represents sodium, potassium, ammonium, triethanolamine and other organic amines.

This compound, Polypeptide No. 37, contains from 41 to 45 percent of the characterizing sodium salt as its active ingredient and from 37 to 43 percent protein, as computed from Kjeldahl Nitrogen determinations showing 5.92 to 6.88 percent nitrogen.

3. Sodium N-Lauroyl Sarcosinate (e.g., "SARKO-SYL NL-97", manufactured by Geigy Industrial Chemicals Division of Geigy Chemical Corporation), consisting of the sodium salt of an amido-methylated lauric acid having the structure:-

wherein

R represents the fatty substituent from lauric acid containing from 10 to 11 carbon atoms, and

M represents sodium, potassium, ammonium, triethanolamine and other organic amines.

It has been found that the protein type surfactants

above specified, as well as the surfactant marketed as Sarkosyl NL-97, which is the sodium salt of an amido-methylated lauric acid, have the common property when combined with the caustic alkali and alcohols of effectively inhibiting the corrosive action of the caustic upon the human skin and mucosa.

Also included in the concentrate is a humectant in the form of relatively non-evaporative, high boiling polyhydric alcohols, such as glycerol, ethylene glycol, propylene glycol and dipropylene glycol. These glycols not only prevent too rapid drying out of the concentrate but also act as humectants for maintaining the caustic alkali in an active state when the aqueous concentrate is applied to a surface to be cleaned which has been preheated to a temperature of 200° F.

While the concentrate of the present invention consisting essentially of an aqueous solution of the caustic alkali, the surfactants and the glycols as above mentioned may be effectively used when applied as a liquid to the soiled surface to be cleaned, its use is greatly facilitated when it is applied in the form of a foam dispensed from an aerosol container. To this latter end the concentrate preferably may include a foam-forming and stabilizing agent in the form of an anionic fatty acid soap, which is obtained through introduction into the concentrate of oleic acid and an alkanolamine, such as monoethanolamine, diethanolamine or triethanolamine. This fatty acid soap constituent of the concentrate serves not only as an additional emulsify-

30

ing agent for the propellant when the concentrate is packaged in an aerosol container but also as a stabilizing agent for the foamed concentrate expelled from the 40 pressurized container when the discharge valve thereof is opened. The alkanolamine further combines and acts synergistically with the caustic alkali to more effectively activate the cleansing property of the composition.

45 Combined with the caustic alkali concentrate in the aerosol container is a propellant which may be any one or a mixture of the following: dichloro difluoro methane ("Genetron 12" manufactured by General Chemical Division; "Freon 12" manufactured by Freon Division of E.I. duPont de Nemours Co.; "K 12" manufactured by Kaiser Chemical Division of Kaiser Aluminum & Chemical Sales, Inc.; "Isotron 12" manufactured by Pennsalt Chemicals Corporation and "Ucon 12" manufactured by Union Carbide Chemicals Corp.) and dichloro tetra-fluoro ethane ("Genetron 114" — General Chemical; "Freon 114" — I.I. duPont de Nemours; "K 114" — Kaiser Aluminum; "Isotron 114" — Pennsalt Chemicals and "Ucon 114" — Union Carbide).

50 In lieu of the above described propellant, there may be employed in the composition of the present invention other conventional hydrocarbon propellants, such as butane, isobutane, propane and mixtures thereof. By substituting a judicious quantity of such hydrocarbon propellant for the fluorocarbon propellant content of the composition to be sprayed from an aerosol container, as by introducing into the composition a hydro-

55

carbon propellant in an amount of from 3 to 4.5 percent by weight of the composition as against about 6 percent by weight of the aforesaid fluoro carbon propellant, the composition containing the hydrocarbon propellant is non-flammable.

The non-flammable property of the composition containing the hydrocarbon propellant in accordance with the present invention is an important attribute thereof since it is desirable, for most effective cleansing of oven soils, to spray the composition into the oven pre-heated to a temperature of approximately 200° F. This elevated temperature of the surfaces to be cleaned not only potentiates the action of the caustic on the oven soils, but also effects such instant volatilization of the propellant vapors as to enable them to rapidly flash off and be carried away by the hot air convection currents.

All of the above-mentioned propellants are substantially insoluble in the aqueous concentrate, but instead combine there-with to form a liquid emulsion which, upon its discharge from the dispensing container, and impingement against the surface to be cleaned, effectively forms a stabilized blanket of foam over said surface to soften, dissolve and emulsify the burnt on fats and other deposits so that the same may be readily removed by a simple wiping treatment.

When, however, it is desired to use the concentrate of the present invention as a liquid preparation as distinguished from a foam-forming composition, it may be desirable to incorporate in the concentrate, in lieu of the fatty acid soap stabilizer, a thickening agent such as sodium carboxy methyl cellulose (CMC), amyo pectine starch or other compatible additive which is soluble or at least readily dispersable in the concentrate to render it more or less viscous as may be desired so that it may properly blanket and adhere to the surface to be cleaned.

It will be noted from the formulae examples hereinafter set forth that in both the liquid and the foam-forming compositions, the percentages by weight of the basic ingredients thereof which act synergistically to maximally inhibit the corrosive action of the caustic alkali upon human skin and mucous membranes, namely, the caustic alkali combined in aqueous solution with the aforementioned polyhydric alcohols and anionic surfactants, may be varied within the following ranges:

Caustic Alkali — 0.5% to 5.0%

Polyhydric Alcohol — 20.0% to 40.0%

"Maypon SK" — 0.3% to 5.0%

"Poly peptide No. 37" — 1.0% to 20.0%

Sodium N-Lauroyl Sarcosinate — 0.5% to 5.0%

Water — 30.0% to 70.0%

Similarly, the additives incorporated in the concentrate, to wit, the thickening agent in the case of the liquid preparation and the foam stabilizer with or without additional thickening agents in the case of the foam-forming preparation, may vary as desired in any amount up to 5 percent in each instance.

As for the propellant, its percentage (also by weight of the total foam-forming composition packaged in the dispensing container) may vary in amount as may be necessary to provide in the aerosol container the requisite vapor pressure for effecting complete discharge therefrom of the cleanser contained therein and effective foaming thereof, which pressure should be within safe limits for the container in which the cleanser is packaged.

The following examples are illustrative of the present invention and provide compositions which have exceptionally high cleaning power when used to remove food residue and burnt-on fat and grease deposits from the surfaces of ovens and the like. Further, and of equal importance, is the fact that in all of these illustrative compositions, the corrosive effect of the caustic alkali content thereof is inhibited to minimize burns or other irreversible injury to the user upon contact of the composition with the skin.

In all of the following examples, the percentage values are by weight of the entire composition:

Except for the surfactants Mapon SK and Polypeptide 37 and the water in the above Examples 10 to 17 all of the remaining ingredients of the compositions are included therein on essentially an anhydrous basis. Also, in these Examples 10 to 17, the percentage stated for the several constituents of each composition are exclusive of the propellant which, as previously stated, is present in the composition in an amount sufficient to force the composition out of the aerosol container as a spray which converts to foam on its impingement upon the surface being cleaned.

In those compositions of Examples 10 to 17 wherein the water content thereof is limited to substantially less than 50 percent of the total weight of the composition, the humectant content is increased proportionately as set forth and also there is included in the composition, with or without the presence therein of the oleic acid soap as a foam stabilizing agent, a proportionate amount of water thickening agents to further stabilize the foam. These thickening agents, in addition to those previously mentioned and which serve to stabilize the foam and to increase its ability to adhere to vertical surfaces, may be of the organic type or the inorganic type as follows:

ORGANIC

Sodium carboxy methyl cellulose
Hydroxy ethyl cellulose
Methyl cellulose
Polysaccharides ("Kelzan" — manufactured by Kelco Company)

INORGANIC (clays and beneficiated clays)

Refined calcium bentonite ("Thycorthin" — manufactured by H.M. Johnson, Inc.)

In use of the product of the present invention, the preferred procedure is to apply it directly upon the surface to be cleaned, preferably after it has been pre-heated as aforesaid, as by spraying the same, when prepared as a foam-forming composition pursuant to Examples 6 to 17 as above set forth, from a pressurized dispensing container to form a covering blanket of foam, or by brushing or otherwise applying the same, when prepared as a non-aerosol composition pursuant to the foregoing Examples 1 to 5, so as to completely cover the soiled surface. After the soiling deposits on the surface undergoing treatment have been softened and emulsified by the applied cleanser composition, they may be readily removed by a simple wiping operation with a damp cloth or sponge. In the case of heavier than normal deposits, a second application of the cleanser may be required followed by the wiping treatment. No preliminary wetting of the soiled surface is necessary, and neither is it necessary to use vinegar or any other agent for neutralizing the active caustic ingredient of the clean-ser composition.

While I have described herein several embodiments of my invention, it will be apparent that it is susceptible of various other changes and modifications without departing from the general principles or real spirit thereof, and it is to be understood accordingly that it is intended to claim the present invention broadly, as well as specifically, as indicated by the claims appended hereto.

I claim:

- 30 1. A liquid composition for cleaning oven, grill and similar surfaces which inhibits the corrosive action thereof on human skin and mucous tissues consisting essentially of an aqueous solution of about 2.5 to 5 parts by weight of sodium hydroxide, about 20 parts by weight of propylene glycol; about 2 parts by weight of a compound having the following general formula:

40 where R represents hydrogen and hydrocarbon groups having from 1 to 7 carbon atoms, R represents fatty substituent of lauric acid made from coconut oils, M represents sodium, and m is an integer averaging 4 and controlled by the degree of hydrolysis; about 1 part by weight of a compound having the formula:

45 Complex, colloidal, magnesium aluminum silicate ("Veegum" — manufactured by R.T. Vanderbilt Co., Inc.)

It is well known that reaction rates approximately double for each 10°C . (18°F .) rise in temperature, so that when the cleansing preparation of the present invention is applied to a surface pre-heated to about 200°F ., representing an increase of some 125°F . over normal room temperature, the preparation will act on and clean soiled surfaces more than 100 times faster than it would at room temperature. Thus, it has been found that the composition of the present invention effectively cleans ovens of burnt-on fatty food residue and the like within a matter of only several minutes, ordinarily if properly applied in about three minutes.

50 where R represents hydrogen and various hydrocarbon groups having from 1 to 7 carbon atoms, n is an integer averaging 20 controlled by the degree of hydrolysis and M is sodium; about 0.75 parts by weight of a compound represented by the formula:

65 where R represents the fatty substituent of lauric acid made from coconut oil, M represents sodium; about 0.3 parts by weight of oleic acid; about 0.6 parts by weight of tri-ethanolamine; and, from about 30 to about 70 parts by weight of water.
